UNITED STATES PATENT OFFICE.

CHARLES G. RADCLIFF, OF CARTHAGE, MISSOURI.

BED FOR INVALIDS.

SPECIFICATION forming part of Letters Patent No. 760,755, dated May 24, 1904.

Application filed September 28, 1903. Serial No. 174,972. (No model.)

To all whom it may concern:

Be it known that I, CHARLES G. RADCLIFF, a citizen of the United States, residing at Carthage, in the county of Jasper and State of Missouri, have invented certain new and useful Improvements in Beds for Invalids, of which the following is a specification.

Persons confined to bed by sickness or other affliction necessitating quiet to effect convalescence and ease are not infrequently sorely tried and their ailment aggravated by the use of the ordinary bed-pan when required.

In accordance with this invention it is not necessary to disturb the patient when relief is desired, as the vessel may be placed in position beneath the invalid and removed after use without having to move the person in the slightest degree to cause pain or discomfort.

This invention provides the mattress with an oblong opening, a mattress-plug of corresponding size and shape to fill the opening, and a vessel having an outer flange at its upper edge to support the vessel in the opening after the plug has been removed. The oblong opening extends crosswise of the bed, and the patient is positioned upon the bed to extend across one end of the oblong opening, thereby admitting of the mattress-plug being removed through the exposed end of the opening and the vessel being placed in position and then slid beneath the invalid.

The invention further consists of a vessel of oblong form adapted to be slipped upward into the opening of the mattress and given a one-quarter turn to engage its flange at opposite ends with the mattress at points corresponding to the minor axis of the opening therein.

The invention further consists of means for reinforcing the mattress at the opening, so as to resist the perpendicular pressure at this point.

For a full description of the invention and the merits thereof and also to acquire a knowledge of the details of construction of the means for effecting the result reference is to be had to the following description and drawings hereto attached.

While the essential and characteristic features of the invention are susceptible of modi-

fication, still the preferred embodiment of the invention is illustrated in the accompanying drawings, in which—

Figure 1 is a perspective view of a mattress embodying the invention, the mattress-plug 55 being removed and the vessel in place. Fig. 2 is a plan view of a modification. Fig. 3 is a section on the line X X of Fig. 2. Fig. 4 is a perspective view of the mattress-plug constructed for use in connection with the form 60 illustrated in Fig. 2. Fig. 5 is a detail section of the construction shown in Fig. 2, the vessel being replaced by the mattress-plug.

Corresponding and like parts are referred to in the following description and indicated 65 in all the views of the drawings by the same reference characters.

The mattress 1 may be of any formation and is provided at an intermediate point with an oblong opening 2, normally closed by means 70 of the mattress-plug 3, which is of a size and shape to snugly fit the opening 2 and obviates the formation of any welts or projecting parts. The oblong opening 2 extends transversely of the mattress and is of a length to admit of an 75 end portion being exposed when the opposite end portion is covered by the invalid extending across the same. This construction enables the mattress-plug to be removed and placed in position without disturbing the patient and also provides for placing the vessel 80 4 in position without causing inconvenience or ill results. After the mattress-plug 3 has been removed the vessel 4 is inserted into the exposed end of the opening 2 and moved along 85 said opening to proper position, being supported by means of the outer flange 5 at its upper end.

In the construction shown in Fig. 2 and the detail views thereof the opening in the mattress is of elliptical form and the vessel is of corresponding shape and of a size to admit of its upper flanged end passing comfortably through the opening, after which the vessel may be given a one-quarter turn to cause the 95 flange at opposite ends in line with the major axis to engage with the sides of the opening at diametrically opposite points corresponding to the minor axis, this being illustrated most clearly in Fig. 2. In this construction the ves- 100

sel is inserted and removed from below the mattress. A reinforcement 6 surrounds the opening and is stitched to the side of the mattress and is stiffened at its inner edge by means 5 of a wire 7 or like stay.

The mattress-plug 3 is provided at its lower end with a plate 8, which projects a short distance beyond the sides of the plug to underlap the portion of the mattress bordering upon the 10 opening 2, as indicated most clearly in Fig. 5, thereby supporting the mattress against perpendicular pressure. The projecting portion of the plate 8 is notched, as shown at 9, to receive cords or tapes 10, which are attached at 15 their upper ends to the reinforcement 6 and pass through the opening 2 and adapted to be tied in a bow-knot beneath the plate 8, so as to support the plug 3, as indicated most clearly in Fig. 5. The advantage of reinforcing the 20 mattress at the opening is evident when it is remembered that the greatest pressure is required to be sustained at this point.

Having thus described the invention, what is claimed as new is—

25 1. In combination, a mattress provided with an oblong opening, a vessel having an outer flange and of corresponding shape to the opening adapted to pass therethrough and to receive a one-quarter turn to cause said flange 30 to engage with the mattress at opposite sides

of the opening and hold the vessel in suspension, substantially as set forth.

2. In combination, a mattress provided with an opening adapted to receive a vessel, a reinforcement surrounding the opening at its upper end and secured to the mattress, a plug for closing said opening, and securing means attached to the reinforcement and passed through the opening and adapted to be tied beneath the plug for supporting the same, substantially as set forth. 35 40

3. In combination, a mattress provided with an opening, a reinforcement applied to the upper side of the mattress and surrounding the opening, a plug for closing the opening, a 45 plate secured to the plug and having an edge portion projected beyond the sides of the plug to underlap the portion of the mattress bordering upon the opening, and securing means attached to said reinforcement and passed 50 through the opening of the mattress and adapted to hold the plug in place, substantially as set forth.

In testimony whereof I affix my signature in presence of two witnesses.

CHARLES G. RADCLIFF. [L. s.]
